Atty.

UNITED STATES PATENT OFFICE.

WALTER CLINT DAYTON, OF BUFFALO, NEW YORK, ASSIGNOR, BY MESNE ASSIGNMENTS, TO GENERAL OIL GAS CORPORATION, OF BRISTOL, VIRGINIA, A CORPORATION OF VIRGINIA.

APPARATUS FOR PROTECTING GAS PRODUCERS.

1,402,721.

Specification of Letters Patent. Patented Jan. 3, 1922.

Application filed November 6, 1917. Serial No. 200,597.

To all whom it may concern:

Be it known that I, WALTER CLINT DAYTON, a citizen of the United States, residing at Buffalo, in the county of Erie, State of New York, have invented certain new and useful Improvements in Apparatus for Protecting Gas Producers, of which the following is a specification.

The present invention relates to an apparatus for generating gas from liquid combustibles, such as fuel oil, and its object is to prevent injury to the apparatus by an excessive rise of temperature in the retort due to a more or less complete failure of feed of the combustible.

In apparatus involving my invention, as described in U. S. Patent #1,174,970, a mixture of oil and air is introduced into a retort maintained at a temperature high enough to cause chemical reaction or partial combustion, resulting in the formation of a combustible fixed gas useful for industrial or domestic heating. Although the feed device for the oil is designed to reduce clogging by foreign material to a minimum, still this contingency is not entirely excluded. I have found that as a result of decrease of oil feed, the temperature in the retort may become dangerously high. Temperature indicating devices have proved to be too sluggish in this contingency to prevent damage to the retort. It also is impracticable to detect directly the decreased flow of oil, as a constant circulation of oil occurs at all events to and from the feed device, the excess oil overflowing and returning to the storage tank whether or not a stoppage in the feed valve occurs. In accordance with my invention, I have provided means dependent on the calorific value of the gas in the retort for indicating any discontinuity of oil feed.

The novel features of my invention will be more fully set forth in the following description taken in connection with the following drawings which show diagrammatically and partly in section the embodiments of my invention.

Referring to the drawing, the apparatus comprises a retort 1, indicated in dotted outline within a housing 2 into which is fed through a pipe 3 a mixture of oil and air supplied from a mixing device, hereinafter described. The products of the combustion emerge from the retort through a pipe 4,

which to advantage is located about the pipe 3 so as to cause a preheating of the unreacted mixture in the pipe 3. The combustible is carried by means of a pump 5 from a supply tank 6, through conduits 7 and 8, to an auxiliary oil receiver 9 from which the excess oil overflows through a conduit 10 back to the oil tank 6. Air under pressure is furnished from a pump 11 mounted upon the same shaft 12 with the oil pump. The compressed air or other combustion-supporting gas, is led through a conduit 13 into the feed device. A branch pipe 14 communicates with the space above the oil in the feed device and another branch pipe 15 communicates with the space above the oil in the supply tank 6 so as to produce an equilibrium. The air under pressure upon passing from pipe 13 into the conduit 3 expands, thereby causing a reduction of pressure at the mouth of the pipe 16. As the full or initial air pressure is exerted upon the oil in the auxiliary receiver 9 in which projects a short conduit 17 communicating with the conduit 16, some of the oil is forced up into the pipe 17, past the needle valve 18 and is caused to emerge in finely divided droplets from the conduit 16 and mixes with the air. By properly regulating the needle valve with a hand-wheel 19 the feed of oil may be set to give a desired proportionality, the setting being observed by means of a pointer 20.

The mixture of oil and air when introduced into the retort which is heated to a temperature of about 750 degrees C. at the beginning of the operation causes a chemical reaction or combustion with the formation of a fixed combustible gas. As already indicated foreign matter getting into the needle valve 18 causes disturbances of the proportionality of oil and air and thereby produces a high temperature in the retort 1, which may be sufficient to cause injury to the retort in the course of a few minutes.

In accordance with my invention I draw from the conduit 4 some of the gas through a tube 21 which communicates with a calorimeter 24. The tube 21 communicates with a gas pump 22 and is thereby led into an expansion chamber 23. Upon the same shaft with the gas pump 22 is an air pump 24, both pumps being operated by an electric motor 25. Air is delivered to the expansion chamber 23. Gas and air are carried respec-

tively by pipes 27 and 28 to the burner 35 of the calorimeter 34. The heat generated by the burning of the gas influences an indicator 29 upon the calorimeter to move in response to the instantaneous calorific value of the gas.

An adjustable arm 30 of brass or other suitable metal is fixed to the calorimeter casing and suitably electrically insulated therefrom. Connected to the end of the adjustable arm 30 is a stirrup shaped wire 31 which is placed over the end of the indicator 29. One terminal of the electrical circuit 32, containing a battery 33, or other suitable source of current, is connected to the adjustable arm 30 and the other terminal of the circuit is connected to the casing of the calorimeter 34 and thus also to the indicator 29. In this circuit is included an electric bell 36 or other suitable signal device.

When the oil feed becomes more or less clogged, the calorific value of the gas drawn by the pipe 21 from the gas delivery conduit 4 changes instantly due to the continuity of feed of the mixture through the retort. The result of the clogging of the valve 18 with the consequent decrease in oil fed, produces a change in the combustion within the retort and, produces a leaner gas, or one of lower calorific value. As a fraction of the gas produced is constantly diverted a change in calorific value of the gas results in a movement of the indicator 29 which, if the clog-

ging is serious enough, closes the electrical circuit including wire 31, the arm 30, the 35 conductor 32 and battery 33 and sounds an alarm, in this case ringing a bell 36. The attendant may then easily remove the obstruction by completely closing and then opening up the needle valve and finally returning the pointer 29 to its normal position.

What I claim as new and desire to secure by Letters Patent of the United States, is:—

The combination of an apparatus comprising a retort and valve controlled means for supplying to said retort a mixture of air and a liquid combustible, a calorimetric device, a pump for supplying to said device a mixture of air and a part of the reaction products from said retort, an electric alarm device, an electric supply circuit for energizing said alarm device connected to a moving element of said calorimetric device, and an adjustable stirrup-shaped contact adapted to contact with said movable element to complete the circuit of said alarm when the calorific value of said reaction products falls due to the clogging of the valve-controlled supply means for said retort.

In witness whereof, I have hereunto set my hand this fifth day of November, 1917.

WALTER CLINT DAYTON.
